ADJUSTABLE TRAY MECHANISM FOR
DUPLICATING MACHINES

Robert F. Morrison, Oak Park, and George J. Rundblad, Elmwood Park, Ill., assignors to Ditto, Incorporated, Chicago, Ill., a corporation of West Virginia

Application April 27, 1939, Serial No. 270,276

9 Claims. (Cl. 101—132.5)

This invention relates to duplicating machines and particularly to the delivery trays of such machines.

This invention is particularly adapted for use with the wet-process type of duplicating machine. In this type, copy sheets are fed to a pair of rollers, one of which is moistened with a solvent. As the copy passes between these rollers, one surface of the sheet becomes moistened with a thin film of the solvent. The copy sheet so moistened then passes between a drum and an impression roller, the latter serving to press the sheet against a master sheet carried by the drum, on which master sheet the matter to be copied appears in reverse. This reverse copy is made from an ink which is soluble in the solvent so that as the moistened copy sheet passes between the impression roller and the drum it receives a positive impression from the specially-prepared master sheet. The copy sheet is then ejected tangentially of the drum by the momentum of its movement with the drum so as to be received upon the delivery tray.

It has been observed that the copy sheets are ejected from the drum at different angles, the angles depending upon several factors. Where the copy sheets are long and relatively light, the sheets are ejected in a generally downward direction so as to arrange themselves readily in a neat pile in a tray having a downward slant toward its outer end. Where the copy sheets are long and heavy, they are ejected in a more elevated direction and have a tendency sometimes to overshoot the stop at the outer end of the tray unless the tray is tilted upwardly at its outer end. In system work, where short and long sheets are sent through the duplicating machine in a single run, the stop must of course be located sufficiently forwardly to accommodate the long sheet. At the same time it is important that the short sheets fall toward the rear end of the tray, since if the short sheets are permitted to move to the front against the stop the rear edges of these sheets interfere with the leading edges of the succeeding long sheets and cause the long sheets to buckle so as to disturb the orderly stacking of the sheets on the delivery tray. This effect can be secured by tilting the front end of the tray upwardly.

The principal object of this invention therefore is to provide an improved means for supporting a delivery tray in a manner which will permit the tray to be held at different angles vertically for meeting varied conditions of use of the machine, and to provide an adjusting means of

this type which is simple in operation and inexpensive to construct.

Other objects of this invention will become apparent as the description proceeds. The preferred form of the invention is shown in the accompanying drawings, in which:

Fig. 1 is a plan view of the front portion of a duplicating machine showing the delivery tray in position;

Fig. 2 is a vertical sectional view taken substantially at the line 2—2 of Fig. 1;

Fig. 3 is an enlarged plan view of one of the detents and its cooperating parts, with some of the parts shown in section;

Fig. 4 is a vertical cross sectional view taken substantially at the line 4—4 of Fig. 1; and

Fig. 5 is a vertical cross sectional view taken substantially at the line 5—5 of Fig. 4.

Referring now to the drawings for a detailed description of the invention, 10 represents the frame of the duplicating machine. Said frame 10 supports a feed tray 11 on which copy sheets (not shown) are supported prior to their insertion into the machine. The copy sheets pass between guide means 12 to forwarding rollers 13 and 14. The roller 14 is in contact with a wick 15 of fibrous material which is moistened with a solvent in the moistening mechanism generally designated by reference character 16. After the copy sheet passes between the rollers 13 and 14 it is pressed against a drum 17 by an impression roller 18, for receiving an impression from a form carried by the drum, such form to have the desired data printed thereon in reverse with specially-prepared ink. The rollers 13 and 14 are driven by well-known means which is not a part of this invention and accordingly is not shown in detail.

After passing between the drum 17 and the impression roller 18, the copy sheet is ejected by the momentum of its movement with the drum into position upon a delivery tray 19. The tray is formed from sheet metal, a portion 23 of which is turned upwardly to form the rear transverse wall of the tray. The edge 24 of the upwardly bent portion 23 is additionally bent outwardly as shown to guide the sheets upon the tray. The sides of the tray are formed by upwardly bent portions 25 and 26, said sides being generally triangular in shape. At their rear ends, the sides of the tray are notched as at 27 to receive laterally disposed supporting screws 20 which are threaded into bosses 21 and 22 carried by the frame 10 of the machine. The tray may be oscillated about the screws 20, and when de-

sired, may be slid forwardly off the supporting screws by a movement longitudinally of the tray.

The lateral position of the copy sheets on the delivery tray is determined by spacing bars 28 and 29. These bars are provided with vertical portions 30 and 31, respectively, which serve to restrain the copy sheet against lateral movement on the tray. The rear ends 32 and 33 of the side portions 30 and 31, respectively, are flared outwardly to insure the entrance of the copy sheets into the space defined by the side portions 30 and 31.

The tray is provided with transverse slots 35 and 36 through which pins 37 and 38 carried by the side bars 28 and 29 extend, such pins being provided with cotterpins 39 on their lower ends holding washers 40 and springs 41 in position thereon for holding the side bars adjustably in position. In advance of the slots 35 and 36 (toward the right in Fig. 2) there are additional transverse slots 42 and 43, through which pins 44 and 45 also carried by the side bars extend, such pins having nuts 46 and 47 secured by screw threads on their lower ends. It will be apparent that the spacing bars 28 and 29 may be locked in place by means of the adjusting nuts 46 and 47. In order to provide a cushioning action for the adjusting means, resilient pads 48 are provided between the spacing bars 28 and 29 and the bottom of the tray.

The distance the copy sheets will be permitted to travel in the tray is regulated by a stop member 52. Said stop member is formed from sheet metal and is provided with an upturned front end portion 53 which normally projects into the path of the copy sheet as it is ejected from the machine. The rear portion 54 of the stop member is bent downwardly so that it projects through a slot 57 in the tray below the surface of the tray. Near the end 54 are located opposed notches 55 and 56 in the stop member which form a neck portion adapted to be received within the slot 57 in the tray so as to form a guide for the stop member. The stop member is further secured slidably in position by means of a bolt 58 extending through a slot 58a in the stop member and having a nut 58b holding a washer 58c in position engaging the tray 19 at opposite sides of the slot 57.

The novel adjusting means for the tray comprises rack bars 59 welded or otherwise secured to the bottom face of the tray 19 with their front edges concentric about the pins 20. In the arrangement shown, the bars 59 stand normally in engagement with grooved studs 60 extending inwardly from the frame bars 61, the studs being mounted in position by means of nuts 62 secured by screw threads on reduced portions of the studs extending through slots 63 in the frame bars, as is best shown in Fig. 5. The grooves about the studs are provided in the construction illustrated by machine screws 64 whose heads extend outwardly beyond reduced end portions of the studs, as is clearly shown in Fig. 3. The tray 19 is held in adjusted position laterally by the engagement of the rack bars with the grooved studs without interfering with the swinging movement of the tray. The tray is also held by the lugs 60 and the rack bars against movement forwardly out of engagement with the supporting screws 20.

For cooperation with the rack bars 59, we have provided latch means comprising detents 65 movably supported in position to engage the teeth 66 of the rack bars, the detents in the ar-

rangement shown being formed of sheet metal bent into shape to provide hooks 67 on their rear end portions secured rigidly upon a supporting shaft 68 rotatably mounted in position between studs 69 and 79 extending outwardly from the end plates of the framework 10 of the machine, such shaft being provided with a knob or head 71 at the end at the right in Fig. 5 for effecting a rotary movement of the shaft when desired. The shaft is held against movement longitudinally by a collar 72 thereon adjacent to the stud 69, as is clearly shown in Fig. 1.

The detents 65 are normally held swung to the limit of their movement in counter clockwise direction in Fig. 4 by a coiled spring 73 connected between the frame plate 61 as shown in said figure and a pin 74 extending from the shaft 68, such spring serving to hold the detents releasably in engagement with the teeth 66 of the rack bars 59 so as to support the tray 19 from said shaft 68. Whenever the operator desires to lower the tray 19, he turns the shaft 68 in clockwise direction in Fig. 4 through the medium of the head 71 so as to carry the detents out of engagement with the rack bars, whereupon the tray is free to move downwardly to the desired adjusted position. Whenever the operator desires to raise the tray 19, this can of course be accomplished by upward pressure on the tray without any preliminary retraction of the detents, the upward movement of the tray being limited by the hooks 75 on the detents 65 engaging pins 76 on the rack bars 59.

For limiting the rotary movement of the rock shaft 68, we have provided a pin 77 extending from the shaft through a notch 78 in the edge of a rib 79 carried by the inner face of the end frame plate, as shown in Fig. 4. This pin by engagement with the ends of the notch holds the shaft against rotary movement beyond that desired.

The adjusting mechanism above described provides a means for changing the angle of the tray with respect to the drum so that it may be elevated for heavy sheets or for system work, and lowered for light sheets. The adjusting means does not interfere with the removal of the tray, and does not interfere with the secure attachment of the tray in operative position during operation of the machine. The arrangement is such that the adjustment of the angular position of the tray does not effect the effective length of the tray as controlled by the stop member 52 and that an adjustment of the effective length of the tray does not change its angular position. A single control knob suffices for the manipulation of the tray supporting mechanism, so as to leave the operator free to swing the tray by hand into the desired adjusted position.

It is to be understood that the foregoing description is merely illustrative of a preferred embodiment of the invention and that the scope of the invention is not to be limited thereto but is to be determined by the appended claims.

We claim:

1. In a duplicating machine of the liquid process type having a drum arranged to carry around a master sheet against which a series of copy sheets are pressed one at a time by an impression roller for taking copies therefrom and are then ejected tangentially of the drum by the momentum of their movement with the drum, the combination of a delivery tray for receiving said sheets after they leave the impression roller, means for pivotally supporting said tray, a rack

bar fixedly mounted on said tray having a series of teeth arranged concentrically about the axis on which said tray is pivotally mounted, and latch means pivotally mounted on a fixed axis adapted by engagement with said rack bar teeth to hold the tray in adjusted angular position.

2. In a duplicating machine of the liquid process type having a drum arranged to carry around a master sheet against which a series of copy sheets are pressed one at a time by an impression roller for taking copies therefrom and are then ejected tangentially of the drum by the momentum of their movement with the drum, the combination of a delivery tray for receiving said sheets after they leave the impression roller, and means for pivotally supporting said tray in adjustable angular position comprising spaced rack bars movable with the tray, detents pivotally mounted on fixed axes adapted by engagement with the rack bars to hold the tray against downward movement, and common means for controlling said detents.

3. In a duplicating machine of the liquid process type having a drum arranged to carry around a master sheet against which a series of copy sheets are pressed one at a time by an impression roller for taking copies therefrom and are then ejected tangentially of the drum by the momentum of their movement with the drum, the combination of a delivery tray for receiving said sheets after they leave the impression roller, and means for pivotally supporting said tray in adjustable angular position, comprising spaced rack bars movable with the tray, a rock shaft rotatably mounted adjacent to said tray, and detents fixedly mounted on said rock shaft so as to rock therewith in position to engage said rack bars for holding the tray releasably in adjusted position against downward swinging movement.

4. In a duplicating machine of the liquid process type having a drum arranged to carry around a master sheet against which a series of copy sheets are pressed one at a time by an impression roller for taking copies therefrom and are then ejected tangentially of the drum by the momentum of their movement with the drum, the combination of a frame, a delivery tray pivotally mounted on said frame below said drum and removable by a movement longitudinally of the tray, a rack bar arranged concentrically about the axis on which said tray is pivotally mounted, latch means mounted on said frame adapted by engagement with the teeth of said rack bar to hold the tray in adjustable angular position, and a lug carried by the frame adapted by sliding engagement with said rack bar to hold said tray against longitudinal movement out of engagement with said frame.

5. In a duplicating machine of the liquid process type having a drum arranged to carry around a master sheet against which a series of copy sheets are pressed one at a time by an impression roller for taking copies therefrom and are then ejected tangentially of the drum by the momentum of their movement with the drum, the combination of a frame, a delivery tray pivotally mounted on said frame below said drum and removable by a movement longitudinally of the tray, a rack bar arranged concentrically about the axis on which said tray is pivotally mounted, latch means mounted on said frame adapted by engagement with the teeth of said rack bar to hold the tray in adjustable angular position, and a grooved lug carried by the frame

5 adapted by engagement with said rack bar to hold the tray against movement laterally and to hold the tray normally against movement longitudinally of the tray out of engagement with the frame.

6. In a duplicating machine of the liquid process type having a drum arranged to carry around a master sheet against which a series of copy sheets are pressed one at a time by an impression roller for taking copies therefrom and are then ejected tangentially of the drum by the momentum of their movement with the drum, the combination of a frame, a delivery tray pivotally mounted at one end on said frame in position to receive the sheets from said drum and impression roller, spaced rack bars movable with the tray, a rock shaft rotatably mounted adjacent to said tray, detents fixedly mounted on said rock shaft so as to rock therewith in position to engage said rack bars for holding the tray releasably in adjusted position against downward swinging movement, means for limiting the rotary movement of said rock shaft in either direction, and yielding means normally urging said detents in the direction for engagement with the teeth of said rack bars.

7. In a duplicating machine of the liquid process type having a drum arranged to carry around a master sheet against which a series of copy sheets are pressed one at a time by an impression roller for taking copies therefrom and are then ejected tangentially of the drum by the momentum of their movement with the drum, the combination of a frame, a delivery tray for receiving said sheets from said drum and impression roller, means for pivotally supporting said tray in adjustable angular position comprising spaced rack bars movable with the tray, and detents pivotally mounted on fixed axes adapted by engagement with the rack bars to hold the tray against downward movement, and releasable means adapted normally to limit upward movement of said tray.

8. In a duplicating machine of the liquid process type having a drum arranged to carry around a master sheet against which a series of copy sheets are pressed one at a time by an impression roller for taking copies therefrom and are then ejected tangentially of the drum by the momentum of their movement with the drum, the combination of a frame, a delivery tray for receiving said sheets from said drum and impression roller, means for pivotally supporting said tray in adjustable angular position comprising spaced rack bars movable with the tray, and detents pivotally mounted on fixed axes adapted by engagement with the rack bars to hold the tray against downward movement, and hook means carried by said detents adapted by operative engagement with said rack bars normally to hold said rack bars against upward movement out of engagement with said detents.

9. In a duplicating machine of the liquid process type having a drum arranged to carry around a master sheet against which a series of copy sheets are pressed one at a time by an impression roller for taking copies therefrom and are then ejected tangentially of the drum by the momentum of their movement with the drum, the combination of a frame, a delivery tray pivotally mounted on said frame below said drum and removable by a movement longitudinally of the tray, a rack bar arranged concentrically about the axis on which said tray is pivotally mounted, latch means mounted on said frame

adapted by engagement with the teeth of said rack bar to hold the tray in adjustable angular position, a lug carried by the frame adapted by sliding engagement with said rack bar to hold said tray against longitudinal movement out of engagement with said frame, a pin extending from one face of said rack bar near its lower

end, and a hook carried by said latch means adapted by engagement with said pin normally to hold said rack bar against upward movement out of engagement with said latch means.
